Primary Examiner — Mimosa De(74) *Attorney, Agent, or Firm* — Andrus Intellectual Property Law, LLP(57) **CLAIM**

The ornamental design for a chair, as shown and described.

DESCRIPTION

FIG. 1 is an isometric view of a chair incorporating my new design;

FIG. 2 is a front elevation view thereof;

FIG. 3 is a rear elevation view thereof;

FIG. 4 is a right side elevation view thereof, wherein the left side elevation view is a mirror image thereof; and,

FIG. 5 is a top plan view thereof.

The portions shown in broken lines illustrate environment only and form no part of the claimed design.
